UNITED STATES PATENT OFFICE

NORMAN B. HURD, OF NEWINGTON, CONNECTICUT, ASSIGNOR TO THE AMERICAN HARDWARE CORPORATION, OF NEW BRITAIN, CONNECTICUT, A CORPORATION OF CONNECTICUT

LOCK

Application filed September 25, 1930. Serial No. 484,345.

This invention relates to locks for doors and the like.

Broadly speaking the main object of the invention is to simplify the lock mechanism 5 without sacrificing strength, durability or operativeness.

Many advantages will be apparent to a mechanic skilled in this art from a reading of the following specification and an examination of the accompanying drawing, which illustrates a preferred form of the invention, it being understood that various changes and modifications may be made from the form shown and described without 10 avoiding the scope of said invention and the claims therefor.

In the drawings—

Fig. 1 is a view of the rear or inner side of the lock case with the cap removed, said view 20 being partly broken away to show details of construction;

Fig. 2 is an edge view of the mechanism shown in Fig. 1, looking up, a portion of the case being shown in section with the keeper shown partly in elevation and partly in section;

Fig. 3 is a perspective view of a detail of construction.

1 represents the lock case, having at its 30 forward edge one or more forwardly projecting lugs or ears 2—2. 3 is a keeper having one or more lugs or ears 4 adapted to stand in the spaces between the lugs 2—2 when the door to which the lock is applied is closed. One or more bolt ends 5 are carried in one or more of the ears 2, the same being movable toward and from the ears 4—4, which latter have passages to receive the ends 35 of the bolts 5 for the purpose of locking the door, the mechanism within the lock case being designed to project and retract the bolt ends 5 at the will of the operator. 6 is a bolt slide mounted within the lock case 1 between two guides 7—7. The bolt ends 5 are carried by the slide 6 so as to be moved therewith. It will be noted that the slide operates vertically in the lock case when the latter is applied horizontally to the door, that is 45 to say, the movement of the bolt slide and bolt is parallel or generally parallel to the front edge of the lock.

At the rear of the bolt slide 6 are two spaced lugs 8—8', which are designed to be engaged by roll-back mechanism, whereby 55 the slide may be shifted up and down in the case from its locking to its unlocking position and vice versa. 9 is a knob suitably mounted on the indoor side of the lock case 1, so that it may be freely rotated by hand. 10 is a roll-back mounted on the knob shank within the case, the end of said roll-back being adapted to alternately engage the lugs 8—8', not only for the purpose of shifting the bolt slide 6, but for the added purpose 60 of blocking said slide against movement when it is shifted to either of its extreme positions. In Fig. 1 of the drawings it will be seen that the end of the roll-back 10 bears against the end of lug 8', positively holding 70 the bolt slide 6 in the unlocking position. Two stops 11—11' limit the turning movement of the roll-back 10. In Fig. 1 of the drawing the roll-back 10 rests against the stop 11' and is yieldingly held in said position by a spring 12. When the roll-back 10 is turned away from the stop 11' and toward the stop 11, the roll-back 10 first becomes 75 freed from the lug 8'. It next engages against the side of the lug 8, so that the continued rotation of said roll-back will move the bolt slide 6 toward the locking position. When the slide 6 reaches its locking position the end of the roll-back 10 leaves the side of the lug 8 and will bear against the end of 80 said lug, thus positively blocking a reverse movement of the slide 6.

14 is a key-controlled roll-back, which is suitably mounted for rotation on the cover or cap 15. 16 represents a portion of a cylinder lock of any suitable construction operable by an appropriate key, not shown but well understood in the art. 17 is a spindle, which is rotatable by the use of a suitable key in a cylinder lock. This spindle fits into 85 a passage through the hub of the roll-back 14, so that when the spindle is turned it will turn said roll-back. When the key is withdrawn from the lock the normal position of the key-controlled roll-back 14 is that shown 90

100

in Fig. 1. The cylinder lock, if desired, may be made adjustable in any suitable way to accommodate the lock of doors of different thicknesses. Such adjustments being well known I deem it unnecessary to describe the same herein, although one such adjustment is shown in Fig. 2 of the drawing.

5 The spindle 17 is sufficiently long to permit said adjustment and when close adjustment is made the inner end of the spindle 10 may extend freely through the roll-back 10 and knob shank 9, so that it may be turned independently thereof.

15 18 is what I will term a coupler. This coupler is pivoted at 19 to the lock case, so that it may oscillate. The pivot 19, in the particular form shown, is located approximately at the end of the key-controlled roll-back 14. The inner part of the coupler is 20 cut away to provide clearance, while at the upper and lower edges of said coupler are provided two offset flanges or bearing shoulders 18'-18", which stand in the path of rotation of the end of the roll-back 14. 25 Between the shouldered portions 18'-18" is a bridge 20 in which there is a slot 21. A pin 22 on the knob-controlled roll-back 10 projects into said slot 21, as best seen in Fig. 1.

30 The operation of the lock is as follows. As already stated, the inside knob 9 may be operated at any time to turn the roll-back 10 to operate the bolt slide 6, to lock or unlock the door. To operate the lock from the 35 outside a suitable key is introduced into the cylinder lock 16. This permits the roll-back 14 to be turned. Assuming the parts stand in the unlocking position shown in Fig. 1; if the roll-back 14 is turned in a clockwise 40 direction its end will clear the shoulder 18" on the coupler, and as it continues to turn it will engage the shoulder 18' on said coupler, so as to rock said coupler in a direction to rotate the roll-back 10, which it does 45 through the medium of the coupler engagement with the pin 22. This necessarily causes the roll-back 10 to turn to first free and then shift the bolt slide from the unlocked to the locking position, as previously 50 described. When the roll-back 10 has reached the locking position it bears against the end of the stop 11, in which position it is yieldingly held by spring 12. The design of the shoulder 18' is such that it provides 55 clearance for the end of the key-controlled roll-back 14 when the door is locked, thus permitting said roll-back to continue to turn until it reaches its normal position, shown in Fig. 1, whereupon the key may be withdrawn. The door will then be locked and 60 will remain locked until it is unlocked either by the knob 9 at the inside or by use of a key at the outside.

From the foregoing it will be seen that the roll-back 10 performs the double func-

tion of moving the locking bolt ends into the locking or the unlocking position and of holding the said bolt ends in either of said positions positively against movement, thereby eliminating the necessity of one or more 70 tumblers, tumbler springs, and associated parts heretofore employed in this type of lock.

I claim:

1. In a lock, a keeper, a case, a bolt movable in a direction generally parallel to the front face of the case for engagement with said keeper, movable bolt carrying means within said case, a roll-back operable from one side of the case and engageable with 80 said means to move the same under one condition and block the same against movement under another condition, a second roll-back operable from the other side of said case, a pivotally mounted coupling means between 85 the first and second mentioned roll-backs to transmit rotary motion from the latter to the former.

2. In a lock, a keeper, a case, a bolt movable in a direction generally parallel to the front face of the case for engagement with said keeper, movable bolt carrying means within said case, a roll-back operable from one side of the case and engageable with 90 said means to move the same under one condition and block the same against movement under another condition, a second roll-back operable from the other side of said case, a pivotally mounted coupling means between 95 the first and second mentioned roll-backs to transmit rotary motion from the latter to the former, said coupling means being normally 100 in engagement with one roll-back and at all times normally out of engagement with the other roll-back.

3. In a lock, a keeper, a case, a bolt movable in a direction generally parallel to the front face of the case for engagement with said keeper, movable bolt carrying means within said case, a roll-back operable from one side of the case and engageable with 110 said means to move the same under one condition and block the same against movement under another condition, a second roll-back operable from the other side of said case, a pivotally mounted coupling means between the first and second mentioned roll-backs to transmit rotary motion from the latter to the former, said coupling means being normally 115 in engagement with one roll-back at all times and normally out of engagement with the other roll-back, and a key actuated means for rotating said second mentioned roll-back.

4. In a lock, a keeper, a case, overlapping lugs on said keeper and case, a bolt in the lug on the case and movable transversely thereof to engage the lug on the keeper, movable bolt carrying means inside the case, two roll-backs inside said case for moving said bolt carrying means, one of said roll-backs 120

also operating to block said means against movement, a coupling pivotally mounted on said case for movement by the other roll-back to transmit movement to the first mentioned roll-back.

5. In a lock, a keeper, a case, overlapping lugs on said keeper and case, a bolt carried by a case lug and movable to engage a keeper lug, two roll-backs in said case for operating said bolt and operable respectively from opposite sides of said case, one roll-back operating indirectly on said bolt through the medium of the other roll-back, and a movable coupling pivoted on the case to transmit movement from one roll-back to the other roll-back.

6. In a lock, a keeper, a case, overlapping lugs on said keeper and case, a bolt carried by a case lug and movable to engage a keeper lug, two roll-backs in said case for operating said bolt and operable respectively from opposite sides of said case, one roll-back operating indirectly on said bolt through the medium of the other roll-back, with a pivotally mounted coupling means between said roll-backs, and with a stationary mounting for said coupling means.

7. In a lock, a keeper, a case, overlapping lugs on said keeper and case, a bolt carried by a case lug and movable to engage a keeper lug, two roll-backs in said case for operating said bolt and operable respectively from opposite sides of said case, one roll-back operating indirectly on said bolt through the medium of the other roll-back, with a pivoted coupling means between said roll-backs, with key-controlled means for normally holding the indirectly operating roll-back out of engagement with said coupling means, and with a stationary support for said movable coupling means.

8. In a lock of the character described, a case, a movable bolt carrying slide therein, a roll-back operable from the indoor side of said case to move said slide to advance and retract said bolt and operating to block said slide in the bolt locking position, a second roll-back operable by a key from the outdoor side of said case and operable to unblock said slide and move said bolt through the medium of the first mentioned roll-back, a pivoted coupling between said roll-backs, to transmit movement from the key operable roll-back to the other roll-back.

9. In a lock of the character described, a case, a movable bolt carrying slide therein, a roll-back operable from the indoor side of said case to move said slide to advance and retract said bolt and operating to block said slide in the bolt locking position, a second roll-back operable by a key from the outdoor side of said case and operable to unblock said slide and move said bolt through the medium of the first mentioned roll-back, with a coupling means between said roll-

backs, and a stationary pivot support therefor.

10. In a lock of the character described, a case, a movable bolt carrying slide therein, a roll-back operable from the indoor side 70 of said case to move said slide to advance and retract said bolt and operating to block said slide in the bolt locking position, a second roll-back operable by a key from the outdoor side of said case and operable to 75 unblock said slide and move said bolt through the medium of the first mentioned roll-back, with a coupling means between said roll-backs, said key operable roll-back being normally out of engagement with said coupling means, and a stationary pivot support for 80 said coupling.

11. In a lock of the character described, a case, a movable bolt carrying slide therein, a roll-back operable from the indoor side 85 of said case to move said slide to advance and retract said bolt and operating to block said slide in the bolt locking position, a second roll-back operable by a key from the outdoor side of said case and operable to 90 unblock said slide and move said bolt through the medium of the first mentioned roll-back, with an oscillating coupling means pivoted adjacent one end to said case and engaging the first mentioned roll-back adjacent its 95 other end.

12. In a lock of the character described, a case, a movable bolt carrying slide therein, a roll-back operable from the indoor side 100 of said case to move said slide to advance and retract said bolt and operating to block said slide in the bolt locking position, a second roll-back operable by a key from the outdoor side of said case and operable to unblock said slide and move said bolt through 105 the medium of the first mentioned roll-back, with an oscillating coupling means pivoted adjacent one end to said case and engaging the first mentioned roll-back adjacent its 110 other end, with shoulders on said coupling means for engagement by said key actuated roll-back.

13. In a lock, a case, a lock bolt, a roll-back for throwing said bolt, a second roll-back, coupling means for causing said second roll-back to actuate said first mentioned roll-back to throw said bolt, and a pivot on which said coupling is mounted to rock.
